UNITED STATES PATENT OFFICE.

ELWOOD HAYNES AND ELMER APPERSON, OF KOKOMO, INDIANA.

MOTOR-VEHICLE.

SPECIFICATION forming part of Letters Patent No. 673,619, dated May 7, 1901.

Application filed July 13, 1900. Serial No. 23,448. (No model.)

To all whom it may concern:

Be it known that we, ELWOOD HAYNES and ELMER APPERSON, of Kokomo, in the county of Howard and State of Indiana, have invented certain new and useful Improvements in Motor-Vehicles; and we do hereby declare that the following is a full, clear, and exact description thereof, reference being had to the accompanying drawings, and to the letters of reference marked thereon, which form a part of this specification.

This invention relates to improvements in motor-vehicles, and has reference more especially to the driving-gear mechanism for transmitting motion from the motor on the vehicle to the driving-wheels thereof.

The invention also embraces other features of construction in motor-vehicles; and the invention consists in the matters hereinafter set forth, and more particularly pointed out in the appended claims.

In the drawings, Figure 1 is a vertical section of a motor-vehicle embodying our invention, taken in a plane outside the vehicle-body. Fig. 2 is a plan view of the driving-gear mechanism and the running-gears of the vehicle, showing in outlines the relation of the body of the vehicle thereto. Fig. 3 is a transverse vertical section taken on the line 3-3 of Fig. 1. Fig. 4 is a transverse vertical section of the driving-gear mechanism, taken on the line 4-4 of Fig. 1. Fig. 5 is an end view of the parts shown in Fig. 4 looking from the right-hand end thereof. Figs. 6 to 16 are details of the driving-gear mechanism, hereinafter to be explained. Fig. 17 is a view, partly in top plan and partly in section, of a distance-rod used between the connected driving-gears on the body and running-gears, said view showing the connection of the said rod with the several gears. Fig. 18 is an axial section of an antifriction-bearing located between the differential gear mechanism of the rear axle and the adjacent wheel. Fig. 19 is a transverse section on the line 19-19 of Fig. 18. Fig. 20 is a sectional detail of the connection between the longitudinal frame members of the running-gear frame and the front axle. Fig. 21 is a vertical section on the indirect-line 21-21 of Fig. 20.

First referring to the general construction of the vehicle, A designates the vehicle-body,

supported on a running-gear consisting of a front axle B, carrying wheels C C, a rear axle D, having wheels E E, and two horizontally-arranged longitudinal frame-pieces F F, which are attached at their rear ends to the rear axle near the ends of said axle, and which frame-pieces converge at their forward ends and are there united and connected with the front axle near the longitudinal center thereof. The body A is supported from the ends of the front axle B by means of springs A' A' and from the rear axle by springs A² A², said springs being shown as of the usual elliptical form. The said frame-bars F F are connected rigidly with the rear axle, but are pivotally connected with the front axle by a horizontal pivot arranged transversely of the axle in a manner permitting the said front axle to swing in a vertical plane, said axle being incapable of any horizontal movement with respect to the main frame. This construction permits one of the wheels C to be raised above or below the other in passing over an obstruction or a depression in the ground without communicating motion to the body. Such pivotal connection of the frame-bars F F with the axle is shown in Figs. 1, 2, 20, and 21 of the drawings, and is made as follows: B' designates a plate, which is connected with said bars by a bolt b', passing through rearwardly-directed lugs b² on said disk, and a cast fitting F^c, by which the bars F F are united at their forward ends. Said plate B' is pivotally connected by a horizontal pivot-stud b³ with a sleeve B², attached to the front axle B and having an irregularly-shaped flange b⁴, which bears against the front face of the plate B'. Said stud b³ is provided at its outer end with a screw-threaded nut b⁵, which holds the sleeve B² in place thereon. Said sleeve B² is attached to the axle by dropping or offsetting said axle at the center thereof and providing said sleeve at its front end with a vertical flange b⁶, between which and the lower part of the flange b⁴ said offset part b⁷ of the axle passes. Said flange b⁶ and the lower part of the flange b⁴ are of the same general form and of a length equal to that of the offset part of the axle. The axle is clamped between said flanges by means of bolts b⁸, passing through the lower margins thereof below the axle. The outer ends of the axle are pro-

vided with horizontal pivoted axle-sections B³, on which the steering-wheels C are mounted. Said shaft-sections are provided with forwardly-extending rigid arms B⁴, to the outer 5 end of which are attached connecting-rods b⁵. The inner ends of the connecting-rods are pivoted to arms on the forward end of a horizontal lever B⁶, which is actuated from a vertical rotative steering-shaft B⁷, which latter passes upwardly through the body of the vehicle in front of the driver's seat and is provided with an operating-handle b⁹. Said horizontal lever B⁶ is rigid with a rotative vertical pivot-shaft b¹⁰, which is operatively-connected with said shaft B⁷. Said operative connection between the shaft B⁷ and lever B⁶ includes a spring B⁸, which permits vertical movement of the body relative to the axle, and said pivot-shaft has rotative bearing in 20 a forwardly-extending lug B⁹, connected with the flange b⁶ of the bearing-sleeve B².

Next referring to the driving-gear mechanism, which constitutes the principal feature of our invention, said mechanism and the parts associated therewith are made as follows: The rear driving-axle D is mounted in bearings D' D², attached to the rear supporting-springs A², the body of the vehicle being provided with laterally-extending brackets a, 25 to which the said springs are attached. The motor for driving the vehicle in the instance illustrated is a gas-engine having two power-cylinders (marked E^a E^a) connected by a central crank-housing E⁴. Any other form of motor may be employed, however, so far as the features constituting our invention are concerned. Said motor-cylinders are supported at their front and rear ends upon transverse horizontal girders A³ A⁴, which extend between and are attached to the side 30 walls of the vehicle.

E' designates the crank-shaft of the engine, which passes through and has bearing in the central crank-housing of the motor. Said 45 crank-shaft is provided at one end with a fly-wheel E² and is journaled at its other end in a bearing-box a', formed on the upper end of a vertical arm A⁵, which latter is attached to a horizontal frame member A⁶, extending between the cross-girders A³ A⁴ of the vehicle-body.

F^a designates a counter-shaft arranged parallel with the crank-shaft and preferably thereunder. Said counter-shaft is journaled 55 at one end in a bearing-box A⁷, extending from the frame member A⁶ and connected in the instance shown with the upright arm A⁵. The said counter-shaft is journaled near its other end in a depending bearing-bracket e, 60 connected with the under side of the crank-housing E⁴ of the engine. Said bearing-shaft is connected by a gear mechanism with the counter-shaft F^a, whereby the latter may be rotated from the former, and the counter-shaft is provided laterally outside of the bearing e with a sprocket-wheel F', through 65 which power is communicated to the rear

axle. The rear axle embodies in its construction an equalizing-gear mechanism which may be of the usual or any preferred form. In 70 the instance illustrated said axle consists of two shaft-sections D³ D⁴, to the outer end of each of which one of the driving-wheels E is attached. The shaft-section D⁴ engages the bearing D' and the shaft-section D³ the bearing D², said bearings having the form of short tubes or sleeves to which the supporting-springs are attached. That end of the shaft-section D⁴ adjacent to the section D³ is surrounded by a sleeve D⁵, which is flanged at 80 its outer end and is attached to said shaft-section D³ by means of bolts or the like passing through said flange and a flange on said section D³. Said sleeve D⁵ is provided on its inner end with a bevel-gear d.

D⁶ designates a collar which is keyed or otherwise non-rotatively secured to the shaft-section D⁴ and is provided on its end adjacent to the sleeve D⁵ with a bevel-gear d'. D⁷ designates a gear-wheel mounted on said 90 axle, the hub d² of which is interposed between the beveled gears d d'. Between said hub and rim of the wheel in the web thereof are mounted a plurality of beveled pinions d³, which mesh with the beveled pinions d d' on 95 the collars D⁵ and D⁶.

The operation of the equalizing-gear mechanism described is familiar and need not be further referred to. The gear-wheel D⁷ of the differential gear mechanism intermeshes with 100 a gear-pinion G, which is mounted on a shaft G', fixed to the upper end of an arm D⁸, which at its lower end has oscillatory or pivotal connection with the running-gear frame, so as to afford oscillatory movement of the said shaft 105 G' toward and from the shaft F^a. Said arm D⁸ rises from the rear axle and is pivotally connected with the running-gear frame concentrically with said axle. As herein shown, 110 said arm is provided at its lower end with a tubular part or sleeve d', which surrounds the inner end of the bearing D' and is adapted to turn thereon, so as to afford oscillatory movement in the upper end of said arm D⁸.

The oscillatory shaft G', as shown in the drawings, has the form of a stub-shaft secured at one end in the arm D⁸, and the gear-pinion G is shown as mounted to rotate on said oscillatory shaft, said gear-pinion being located on the inner side of said arm. Said gear-pinion G is provided with an elongated hub or sleeve g, and upon said extended hub or sleeve is non-rotatively secured a sprocket-wheel G², the construction and arrangement being such that said sprocket-wheel is in line 115 with the sprocket-wheel F' of the counter-shaft F^a. Motion is communicated from the sprocket-wheel F to the sprocket-wheel G² through the medium of an endless chain belt G³.

The gear-pinion G and the equalizing-gear mechanism described constitute the operative connection between the counter-shaft and the rear driving-axle. In view of the fact that

the sprocket-wheel F' is supported on the vehicle-body and the sprocket-wheel G^2 is supported on the running-gear of the vehicle there necessarily exists more or less relative vertical movement between said wheels, which is provided for by the construction next to be described.

Between the counter-shaft F^a and the stub-shaft G' extends a distance-rod H , which is attached at its forward end to a ring H' , surrounding the bearing e of the counter-shaft, as shown in Fig. 17, and is provided at its rear end with fork-arms h h , which are pivotally connected with the arm D^8 , concentrically with said shaft G' . As a convenient construction said fork-arms are pivoted one to the arm D^8 concentrically with the stub-shaft G' and the other to the end of the said stub-shaft outside of the gear and sprocket wheels mounted thereon. Said distance-bar is made extensible, as shown in the drawings, for the purpose of varying the distance between said sprocket-wheels, and therefore the tension on the chain. With this construction it will be obvious that as the sprocket-wheel F' rises and falls by reason of the depression and elevation of the vehicle-body the sprocket-wheel G^2 will be permitted to move slightly toward and from the shaft F' , and owing to the rigid connection between said shafts F^a and G' afforded by said distance-bar a uniform distance between the sprocket-wheels will be maintained.

Next describing the change-speed-gear mechanism, which constitutes a principal feature of our invention, the same is shown in detail in Figs. 4 to 16, inclusive, and is made as follows: The crank-shaft E' is provided with a plurality of gear-pinions I I' I^2 I^3 , located side by side thereon and keyed or otherwise non-rotatively secured to said shaft. The gear-wheels I I' I^2 mesh with gear-wheels (designated as a whole by J J' J^2) which are mounted on the counter-shaft F^a . The construction of the last-mentioned gear-wheels is such that either of the same may be connected rigidly with the counter-shaft F^a , while the others will be free to rotate thereon, whereby motion from said crank-shaft E' will be communicated to the counter-shaft F^a through one of the pinions I I' I^2 and its meshing wheel J J' J^2 , while the other gear-pinions and gear-wheels, which are continuously in mesh with each other, communicate no motion from one shaft to the other. The intermeshing pinions and wheels I I' J J' I^2 J^2 are of varying proportionate diameters, so that the counter-shaft F^a will be driven at varying speeds, according to which one of the wheels J , J' , or J^2 is held from rotation on the shaft F^a .

As herein shown, three different speeds are provided for while the vehicle is running in a forward direction through the three gear-wheels J , J' , and J^2 . In addition to varying the speed of the vehicle means are provided for reversing the direction of motion of the

vehicle, embracing the gear-pinions I^3 at the end of the crank-shaft, the gear-wheel J^3 at the end of the counter-shaft, and an interposed pinion J^4 , which meshes with the gear-pinion I^3 and the gear-wheel J^3 . The gear-pinion J^4 is mounted on a short shaft J^5 , which latter has bearing in the upper end of the arm A^5 , in which the adjacent end of the crank-shank has bearing. Obviously by reason of the interposition of the gear-pinion J^4 between the gear-pinion I^3 and the gear-wheel J^3 the direction of motion transmitted to the gear-wheel J^3 is reversed, and inasmuch as it is only desirable to reverse the vehicle when going at a slow speed the parts last described are so proportioned as to give the desired slow motion to the vehicle.

The gear-wheels J to J^3 , inclusive, are compound in their construction, consisting each of an outer cogged rim J^6 and a central part or hub J^7 , which latter is rigidly secured to the shaft and with respect to which the former may have rotary movement or to which it may be locked when it is desired to drive the vehicle through such gear-wheel. The said gear-wheels J , J' , J^2 , and J^3 are alike, and in the following description thereof one wheel only need to be referred to, it being understood that the description applies equally well to either of the wheels. The outer part J^6 of said gear-wheel is conveniently made of two separate rings j and j' , the former constituting the cogged rim with which the gear-pinions I to I^3 , inclusive, mesh. Said part j' consists of inner and outer annular rigidly-connected cylindric concentric parts or members j^2 j^3 , joined by radial arms, to one side of which inwardly-projecting arms j^a on the outer cogged rim are secured by bolts. The inner part j^3 engages, surrounds, and has bearing on an outer cylindric surface of the inner part or hub j^7 of the wheel. The annular part j^2 extends laterally from the side of the cogged rim of the wheel and affords an annular friction-surface which is surrounded and engaged by a brake-strap k , carried by the said inner part or hub. The inner part or hub is also shown as consisting of inner and outer cylindric parts j^5 j^6 , which are joined by an integral head or web j^7 , which latter is provided with bearing-apertures j^8 for a purpose hereinafter described.

Provision is made for severally operating the brake-bands k , embracing parts connected with or mounted on the hubs J^7 and which are alike on the several wheels J to J^3 and also comprising parts mounted on the counter-shaft F^a , arranged to coöperate with said parts which are mounted on said hubs. Said parts connected with hubs will first be described in connection with one of the wheels only, it being understood that all of them are alike. Attached to the hub J^7 is a radial arm J^8 , which extends outwardly past the friction brake-flange j^2 of the gear-wheel. Mounted in the outer end of said arm J^8 is a short rock-shaft K . Said rock-shaft carries at the outer end

thereof, or that end adjacent to the outer face of the rigid arm, a lever-arm K' , which extends inwardly to and projects over one of the guide-apertures j^8 in the hub J^7 , hereinbefore referred to. The rock-shaft K is also provided with a squared or flat-sided portion, whereby is secured rigidly thereto a short inwardly-projecting arm K^2 . Said arm J^8 is provided with an integral or rigidly-attached cross-piece J^9 , which extends across the face of the brake-flange j^3 and to which one end of the brake-band k is attached by rivets or otherwise, Figs. 9 and 11. Attached to the end or extremity of the band opposite to that which is secured to the said cross-piece J^9 is a metal piece K^3 , which extends beneath the rock-shaft K and is provided with an upturned or outwardly-turned end or lug k' . Said lug projects upwardly at one side of and in position for contact with the arm K^2 on the rock-shaft K , the parts being so arranged that when said rock-shaft is turned by the movement of the free end of the arm K' said short arm of the rock-shaft K will be carried against the lug k' , and by moving said lug laterally thereby tighten the band around the brake-flange j^2 . As shown in the drawings, the rock-shaft K has a bearing at its inner as well as at its outer end on the arm J^8 by means of an outward extension or lug J^{10} , Figs. 6, 8, and 14, which is attached to or forms a prolongation of the cross-piece J^9 , heretofore referred to. Said hub J^7 is shown as also provided with rigid radial arm J^{11} , arranged diametrically opposite the arm J^8 and having a transverse part j^9 , which extends across the brake-band k and acts to hold the same in position.

Now referring to the devices for operating or actuating the several levers K' for tightening the brake-bands or friction-brakes, the same is constructed as follows: Mounted on the shaft F^a , the several gear-wheels, and the bearing e and in such manner as to slide endwise on said shaft is a grooved collar L . Said collar has attached to it four operating-rods $L' L^2 L^3 L^4$, which are arranged longitudinally of the shaft and which extend to and are guided in the guide-apertures j^8 , formed in the hubs of the several gear-wheels on the shaft F^a , as hereinbefore stated. Said operating-rods $L' L^2 L^3 L^4$ are of varying lengths and are adapted to extend to and operate the lever-arms K' belonging to the brake mechanism of the said wheels. As clearly shown in Fig. 15, the said rods L' to L^4 , inclusive, are severally provided with laterally-arranged cam projections $l l' l^2 l^3$, which are so located with respect to the several levers K' as to operate the said levers successively or one at a time when the collar L is moved endwise on the shaft. In other words, said cam projections $l l' l^2 l^3$ are so arranged with respect to the several levers K' that when the collar L is moved to its greatest distance from the several gear-wheels its cam projection l will be engaged with the actuating-lever K' belong-

ing to the wheel J and all of the other cam projections will be free from or out of contact with the other actuating-levers. Movement of the said collar toward the gear-wheels will, however, first bring the cam projection l in engagement with the lever K' belonging to the wheel J' and at the same time carry the cam projection l away from the actuating-lever belonging to the wheel J . Similarly a further movement of the collar L will carry the cam projection l^2 away from the cam-lever engaged by it and bring the cam projection l^2 into engagement with the actuating-lever K' belonging to the said wheel J^2 . When the collar is in its position near the several gear-wheels, the cam projection l^3 will be engaged with the actuating-lever K' belonging to the wheel J^3 . The several cam projections are so arranged as to act laterally on the said actuating-levers K' when the rods to which they are attached are moved endwise, thereby giving lateral movement to the said actuating or lever arms in a direction to tighten the brake-bands around the brake-flanges engaged thereby to afford frictional engagement of the outer parts of the gear-wheels with the hubs on which they turn. When the cam projections are not in engagement with said actuating-levers K' , the latter rest in contact with the sides of the rods $L' L^2 L^3 L^4$, as clearly seen in Fig. 7, the brake-bands at this time being loose, so that the flanges around which they extend may turn freely therein.

For actuating the collar L or, in other words, for moving it endwise on the shaft F^a devices are provided as follows: M is a lever arranged longitudinally of the machine-frame and pivoted at one end to a ring m , which rests in the groove in the said collar L . Said lever M extends forwardly from the shaft F , and at its forward end it is pivotally connected with a transversely-arranged connecting-bar M' , which is pivoted to a lug m' , attached to and extending rearwardly from the forward cross-girth of the machine-frame. M^2 is a bell-crank lever arranged horizontally and pivoted to a forwardly-projecting lug m^2 , attached to the said forward cross-girth of the machine-frame. The bell-crank lever M^2 has an arm which extends longitudinally of the machine-frame and rearwardly from the pivot connecting it with the lug m^2 to a point adjacent to the shaft F , where said rearwardly-projecting arms are connected with the lever M by means of a connecting-bar M^3 . Said bell-crank lever M^2 is also provided with an arm which extends laterally toward the side of the machine-frame and to which is connected an operating-rod M^4 , which extends to the forward end of the vehicle-body and is connected with a hand-lever or other means, by which it may be moved endwise. Such endwise movement of said operating-rod has the effect of moving or shifting the bell-crank lever M^2 on its pivot, and thereby swinging laterally its rearwardly-projecting arm and

- giving lateral movement to the rear end of the lever M, whereby the collar L is shifted endwise upon the counter-shaft F. Obviously the connection of the forward end of 5 the lever M with the machine-frame by means of the connecting-bar M' enables the rear end of said lever M to move in a straight line notwithstanding its pivotal connection with the frame.
- 10 As herein shown, the operating-rod M⁴ is connected at its forward end with a hand-lever N, Fig. 1, which is pivoted on a bracket n, depending from the forward part of the vehicle-body and which rises in front of and at 15 one side of the driver's seat.
- The bearing-box D' for the rear axle is provided with cylindric antifriction-bearing rollers d⁷, which engage the cylindric inner surfaces of said boxes and the periphery of the 20 axle-section, as shown in Figs. 18 and 19 and at the left hand of Fig. 3. Said rollers are held from endwise movement by means of a flange d⁸, engaging the inner ends of the rollers, and a cap d⁹, fitted over the axle and having screw-threaded attachment with the outer 25 ends of the boxes and engaging the outer ends of the rollers. The bearing-box D' will be provided with a similar bearing, with the exception that the opposite ends of the rollers 30 thereof engage closing-caps at both ends of the box.
- We claim as our invention—
1. The combination with a motor and a driving-shaft, of a change-speed gearing comprising a shaft provided with a plurality of fixed 35 gear-wheels, a second shaft provided with a plurality of gear-wheels intermeshing with those on the first-named shaft, said gear-wheels on the second shaft being adapted to turn thereon, means for locking said gear-wheels separately to said second shaft comprising a sliding collar on said second shaft, a plurality of operating-rod^s each provided with a lateral cam projection through the medium of which the locking devices in the 45 wheels are severally operated, and a hand-lever for operating said collar.
2. The combination with a motor and driving-shaft, of change-speed gearing comprising 50 a shaft provided with a plurality of fixed gear-wheels, another shaft provided with a plurality of gear-wheels intermeshing with those on the first-named shaft, said gear-wheels on the second shaft being constructed 55 to turn thereon and being provided with annular friction brake devices acting on said friction-surfaces and embracing operating-levers which extend to points adjacent to the shaft, and an endwise-sliding collar on said 60 second shaft provided with operating-rod^s arranged parallel with said second shaft and provided with cam projections adapted to engage and actuate the said operating-levers.
3. A change-speed gear for motor-vehicles 65 comprising a shaft provided with a plurality of gear-wheels rigidly affixed thereto, a second shaft provided with a plurality of gear- 70 wheels intermeshing with those on the first-named shaft and adapted to turn on said second shaft, said gear-wheels on the second shaft being provided with annular friction-surfaces, brake-bands surrounding said friction-surfaces, arms rigidly attached to the said second shaft with which one end of each of said bands is connected, rock-shafts on said 75 arms provided each with an arm which engages one end of each of said bands, and with an operating-lever which reaches toward the said second shaft, an endwise-sliding collar on the said second shaft and a plurality of operating-bars arranged endwise of said shaft and provided with cam projections which act laterally upon the said actuating-levers.
4. A motor-vehicle comprising a running-gear frame, a vehicle-body movably supported 85 thereon, a motor carried by the body, a rotative shaft mounted on the frame through which motion is transmitted to the driving-wheels and means for transmitting motion from said motor to said shaft comprising a 90 vertically-arranged oscillatory arm pivoted to the running-gear frame concentrically with the said shaft, a gear-wheel on said shaft, a gear-wheel mounted on said oscillatory arm and intermeshing with the gear-wheel on the 95 said shaft, a shaft mounted on the vehicle-body and having operative connection with the motor, a distance-rod pivotally connected with the said free end of said arm and with the body and driving connections between 100 the last-named shaft and the gear-wheel carried by said arm.
5. A motor-vehicle comprising a running-gear frame, a vehicle-body movably supported thereon, a motor carried by the body, a rotative shaft mounted on the frame through 105 which motion is transmitted to the driving-wheels, and means for transmitting motion from said motor to said shaft comprising a vertically-arranged oscillatory arm pivoted to 110 the frame concentrically with the shaft, a gear-wheel mounted on said arm, a sprocket-wheel connected and turning with said gear-wheel, a gear-wheel on said shaft intermeshing with that on said arm, a sprocket-wheel 115 mounted on said body and having operative connection with the motor, a distance-rod pivotally connected with the said arm and acting to maintain the said sprocket-wheel on the body at a uniform distance from that 120 on the said shaft, and a drive-chain engaging said sprocket-wheels.
6. A motor-vehicle comprising a running-gear frame, a vehicle-body movably supported thereon, a motor carried by the body, a rotative shaft mounted on the running-gear frame 125 through which motion is transmitted to the driving-wheels, and means for transmitting motion from said motor to said shaft comprising a vertically-arranged arm pivoted to 130 the frame concentrically with the said shaft, a gear-wheel carried by the movable end of said arm, a sprocket-wheel connected and turning with said gear-wheel, a gear-wheel on

the said shaft intermeshing with the gear-wheel carried by the said arm, a second sprocket-wheel mounted on said body, and having operative connection with the motor, 5 a distance-rod pivotally connected with the said free end of said arm and acting on said second sprocket-wheel to hold the same at a uniform distance from the first-named sprocket-wheel, a drive-chain engaging said 10 sprocket-wheels and means for adjusting the length of said distance-rod.

7. A motor-vehicle comprising a running-gear frame, a vehicle-body movably supported thereon, a motor carried by the body, a rotative shaft mounted on the frame through which motion is transmitted to the driving-wheels, and means for transmitting motion from said motor to said shaft comprising a vertically-arranged oscillatory arm pivoted to 15 the frame concentrically with the said shaft, a gear-wheel mounted on said arm, intermeshing gear-wheels on the said shaft and on a shaft which is carried by the arm, a sprocket-wheel mounted on said body and having operative connection with the motor, a distance-rod pivotally connected with the said free end of said arm and engaged with the sprocket-wheel on the body, and a drive-chain engaging said sprocket-wheel, said distance-rod 20 being provided adjacent to the oscillatory arm with a forked end having pivotal connection with said oscillatory arm at opposite sides of said gear-wheel and sprocket-wheel.

8. A motor-vehicle comprising a running-gear frame, a two-part driving-axle mounted on the frame and provided with an equalizing-gear, a vehicle-body, a shaft on the vehicle-body, which is actuated by the motor and driving connections between said shaft on the 25

vehicle-body and said driving-axle embracing 40 an oscillatory, vertically-arranged arm pivoted to the frame concentric to said driving-axle, an oscillatory shaft carried by said oscillatory arm, a gear-wheel intermeshing gear-wheels on the oscillatory shaft and on the 45 equalizing-gear, and gearing connecting said gear-wheel on the oscillatory shaft with the said shaft on the vehicle-body and a distance-rod between said oscillatory arm and said shaft on the vehicle-body.

9. A motor-vehicle comprising a running-gear frame, a two-part driving-axle mounted on the frame and provided with an equalizing-gear, a vehicle-body, a shaft on the vehicle-body which is actuated by the motor and 55 driving connections between said shaft on the vehicle-body and said driving-axle embracing an oscillatory, vertically-arranged arm pivoted to the frame concentric to said driving-axle, an oscillatory shaft carried by said oscillatory arm, intermeshing gear-wheels on the equalizing-gear and oscillatory shaft, and gearing connecting said gear-wheel on the oscillatory shaft with the said shaft on the vehicle-body, comprising a sprocket-wheel 60 rigidly attached to said gear-wheel on the oscillatory shaft, a sprocket-wheel on said shaft carried by the vehicle-body, and a driving-belt engaging said sprocket-wheels.

In testimony that we claim the foregoing as 70 our invention we affix our signatures, in presence of two witnesses, this 3d day of July, A. D. 1900.
